UNITED STATES PATENT OFFICE.

ROBERT J. MAGOR, OF NEW YORK, N. Y., ASSIGNOR TO MAGOR CAR CORPORATION, OF NEW YORK, N. Y., A CORPORATION OF DELAWARE.

PARTITION END FOR FREIGHT CARS.

Application filed July 31, 1926. Serial No. 126,205.

The invention relates in general to an improvement in the construction at the end of the transverse partitions in freight and other industrial cars and the invention specifically relates to an all metal partition post coacting with the partitions which are usually made of wooden boards.

It is a usual practice in one form of freight car now in general use to bolt a wooden post to the back of a five inch channel post at each side of the car, and to secure the transverse partition to opposite sides of these wooden posts by wood screws or nails. While the cars are in use these partitions especially when made of wood must frequently be replaced as they are surreptitiously removed and used for firewood or for other purposes. The usual screw or nail securing means now in general use are easily removed thus unintentionally facilitating the theft of the partition boards.

Accordingly, one of the objects of the invention is to provide an improved form of partition post and coacting attaching means for securing the partitions in place, which will provide a simple, rugged connection and incidentally to defeat, or at least render difficult, any attempt unlawfully to remove the partitions and particularly to prevent theft of the partition boards.

Another object of the invention is to provide a simplified means for mounting double partitions in position with a single set of fastening means and incidentally provide for a more rugged form of side posts than has been used heretofore and to attain these advantages without materially increasing the manufacturing costs over conventional structures.

Broadly, the invention is attained by securing to the back of the usual five inch channel partition post a bracing channel of less width and by means of screw bolts passed through the partition boards to clamp the reinforcing channel between the boards.

Various other objects and advantages of the invention will be in part obvious from an inspection of the accompanying drawings and in part will be more fully set forth in the following particular description of one form of device embodying the invention, and the invention also consists in certain new and novel features of construction and combination of parts hereinafter set forth and claimed.

In the accompanying drawings:

Fig. 1 is a view in side elevation of part of a freight car side showing the outside of a partition and constituting a preferred embodiment of the invention;

Fig. 2 is a fragmentary view of the partition and adjacent the showing in Fig. 1 and taken on the line 2—2 of Fig. 1, looking in the direction indicated by the arrows; and with parts broken away to show normally hidden structures; and

Fig. 3 is an enlarged detail view taken on the line 3—3 of Fig. 1.

In the drawing, there is shown a car side 10 at one end of a transverse partition 11, it being understood that the structure herein illustrated is duplicated at the opposite end of the partition. The side includes a fabricated all metal partition post formed to include the conventional outer five inch channel member 12 at present found in certain forms of all metal or metal and wood freight cars.

In place of the usual wooden post there is secured to the rear face 13 of the web portion 14 of the outer member 12 an inner channel member 15 secured thereto by a line of rivets 16 and with webs engaging back to back.

The inner channel member 15 is of less width than the outer channel member, and in the instant case is a three inch channel member and is centered relative to the outer channel member and spaced inwardly from each of the flanged edges thereof. The rearwardly projecting flanges 17 of the inner channel member 15 act with the portion of the web 14 extending beyond the same to form a rectangular set into which is fitted the end edges 18 of the partition boards 19.

It is hereby suggested that the partition boards extend in two parallel transverse planes positioned on opposite sides of the inner channel member 15 and are secured together by through bolts 20. In tightening up the bolts the inner channel member 15 is clamped between the inner sides of the parallel partition boards. The bolts are positioned in a vertical line as shown in Fig. 2 and close to the inner channel member as shown in Fig. 3 but they are not necessarily passed through the channel member. Spacing the bolts from the channel members results in saving the necessity of drilling the flanges 17 to accommodate the bolts.

A bolted up structure such as is herein

disclosed is difficult to remove and with such structure in actual use there has been little, if any, loss of partition boards. The boards can be readily fitted between the oppositely disposed outer channel members and even if the boards were not accurately fitted to the oppositely disposed rectangular seats this is immaterial, simply provided that the boards are not cut less than the distance between the oppositely disposed flanges 17 of the inner channel members.

Should one of the partition boards become damaged it can be readily replaced by the car repair man by removing the securing bolts and the new board replaced in position, which can be done by simply cutting off the proper length and boring the necessary bolt holes. The inner channel member provides a reinforcement for the usual outer channel member and braces the same transversely without adding to the space previously occupied by the wooden post.

The structure illustrated provides a somewhat flexible form of partition and a limited amount of wearing is permitted between the partition and the car as a whole as the partition is not positively bolted through any part of the partition post a slight shifting of the portion relative to the post is permitted without detracting from the positiveness of security in fixedly locating the partition against shifting due to the lading in the car.

Spacing the bolts from the ends of the boards as shown in Fig. 2 assists in avoiding the possibility of the bolts ripping out through the end edges of these boards and the structure provides a partition in which there is little, if any, tendency for cracks to form between the top and bottom edges of adjacent boards. The metal posts provide a protection to the end edges of the boards.

While I have shown and described, and have pointed out in the annexed claims, certain novel features of my invention, it will be understood that various omissions, substitutions and changes in the form and details of the device illustrated in its operation may be made by those skilled in the art without departing from the spirit of the invention.

I claim:

1. A partition end for freight cars comprising a metallic partition post including a pair of channel members centered relative to each other and secured together back to back, the inner channel member being of less width than the outer channel member, a pair of parallel partition boards extending from the partition post inwardly and transversely of the car, said partition boards having their end edges abutting the rear face of the outer channel member and their inner sides adjacent said end edges engaging the outer faces of the flanges of the inner chan-

nel member and through bolts passed through the partition boards, disposed adjacent to but spaced exteriorly of the inner channel member and acting to secure the partition boards to the partition post with the inner channel member clamped between the partition boards.

2. A partition end for freight cars including a metallic post comprising an outer channel member, and an inner channel member secured together back to back, a pair of parallel partition boards engaging the post and clamping means spaced from the metal post for securing the boards in position with the inner channel member clamped between the boards.

3. A partition end for freight cars comprising a fabricated all-metal post including a pair of spaced apart inwardly projecting flanges, partitions having their end edges fitted to said post and having their inner side adjacent said edge engaging said flanges and means for securing the partitions to the metal flanges.

4. In a car, a partition structure including a post comprising two channel bars with their web portions back to back, a partition extending inwardly from said post and transversely of the car, an edge of the partition abutting the post and means for securing the partition to the post.

5. In a car, a partition structure including a post, a partition engaging the post and means in spaced relation to the post for clamping the partition to the post.

6. In a car, the combination of a post including a pair of spaced apart inwardly projecting flanges, a pair of parallel partitions having their ends positioned on opposite sides of the flanges and means for clamping the partitions to each other with the spaced apart post flanges therebetween.

7. A fabricated all-metal partition post for freight cars comprising an outer channel member, an inner channel member extending parallel thereto and secured thereto with their web portions back to back, the inner channel member being of less width than the outer channel member, a flange of the inner member coacting with the web portion of the outer member projecting beyond the same to form a rectangular seat adapted to receive the end edge of a transverse partition.

8. An all-metal partition post for freight cars, including a front member, a channel member having its web portion secured thereto, one of the flanges of the channel member coacting with the front member to form a right angled seat for receiving the end edge of a partition.

Signed at New York, in the county of New York and State of New York, this first day of June A. D. 1926.

ROBERT J. MAGOR.
